UNITED STATES PATENT OFFICE.

ROBERT H. OWEN, OF BUTTE, MONTANA.

THRASHING MACHINE.

1,402,534.

Specification of Letters Patent.

Patented Jan. 3, 1922.

Original application filed September 10, 1919, Serial No. 322,796. Divided and this application filed July 23, 1920. Serial No. 398,444.

To all whom it may concern:

Be it known that I, ROBERT H. OWEN, a citizen of the United States, and a resident of Butte, in the county of Silverbow, and 5 State of Montana, have invented certain new and useful Improvements in Thrashing Machines, of which the following is a specification.

This application is a division of the application Serial No. 322,796, filed September 10, 10 1919.

The invention relates to grain thrashers and has reference more particularly to that portion of a grain separator carrying a 15 thrashing cylinder, the principal object being to provide one or more adjustable concaves for the thrashing cylinder, which may be adjusted or set without moving the same from the separator.

20 With this, and other objects in view, the invention consists in certain novel features of construction, arrangement, and combination of parts as will be hereafter fully described and pointed out in the drawings in 25 which

Figure 1 is a view in elevation of one side of the thrashing machine.

Figure 2 is central vertical section through the same.

30 Figure 3 is a plan view of the concaves showing all of them in active position.

Figure 4 is a similar view with one concave in the inactive position.

Figure 5 is a plan view of the thrashing 35 cylinder.

Figure 6 is a side elevation of the thrashing mechanism, showing the means to adjust the concaves.

Figure 7 is a side elevation of the support 40 for the concave sections.

Figure 8 is an elevation of the inner side thereof, the concave sections being in section.

In the drawings, wherein for the purpose 45 of illustration is shown a preferred embodiment of my invention, the numeral 20 designates the framework of the machine supported by front and rear wheels 21 and 22, a casing 23 being carried by said frame.

The numeral 75 designates a thrashing 50 mechanism as a whole arranged in the forward end of the casing 23. This thrashing mechanism includes a rotatable drum 76 car-

ried on a shaft 77 journaled in suitable journal boxes on bearings 78, said shaft being provided at one end with a pulley 79 as 55 clearly shown in Figure 1.

The drum 76 is provided with teeth 80 as shown, and arranged beneath the drum is a concave 81 formed in sections 82, 83 and 84. As more clearly shown in Figure 8, the concave sections are L-shaped in cross section and provided upon corresponding faces with teeth 82' which have shanks extending through openings in the concave section, and held therein by suitable means. The other 60 faces of the concave sections do not carry teeth. The ends of the concave sections 82 and 83 are provided with spaced slots 87 for receiving certain of the teeth when the sections 83 and 84 are swung to the left, in Figure 8. The teeth 82' coat with the teeth 80 of the drum 76 to thresh the grain and it is obvious that the action will be increased or decreased by varying the number of the 65 coacting teeth 82', and for this purpose the 70 concave sections are made adjustable.

The concave sections are rigidly secured to transverse shafts 88 pivoted within elongated slots 89, in vertically adjustable supporting elements, such as segments 90. The 80 shafts 88 are provided with gears 91, rigidly secured to their opposite ends, and these gears engage with curved tracks or racks 92, rigidly secured to the outer faces of the segments or supports 90. Corresponding ends 85 of the shafts 88 are preferably flattened for detachable connection with cranks 93, employed for turning the shaft 88, and adapted to engage abutments 94 which limit the 90 swinging movement of said cranks. When the cranks 93 are in their upper position, the teeth 82' are upright, and when the cranks 93 are swung to a more or less horizontal position, the teeth 82' are more or less inactive.

In order that the supporting elements or segments 90 may be moved toward and away from the drum 76, the rear ends of these segments are provided elongated apertures 96 for the reception of a pivot shaft 97. The 100 forward ends of the segments 90 have recesses 98 in their lower edges receiving a cam rock shaft 99, which has circular ends pivoted within openings in the casing 23.

A hand crank 100 is rigidly secured to this shaft 99, by which it may be turned, and is equipped with teeth 101 to be engaged by a pawl 102, whereby it may be held in adjustable position.

The drum 76 is rotated in the direction of the arrow, as in Figure 2, and discharges the thrashed grain and straw through opening 103, formed by plates 104 and 105. As shown in Figure 4 the plate 105 is provided with slots 106 for the reception of the teeth 82'. Member 105 is the forward end next to concave of the separating grate back of cylinder. The circular openings 105^a in the part 105 are for the purpose to allow more separating grate and are there to allow the grain to fall through. The member 105 constitutes in effect a separating grate, or a stationary concave, said plate 105 is carried by an open stationary, supporting frame 107, arranged over the rear rack or table 26 of grain separator, and is adapted to discharge the straw upon said rack. The straw, with the heads of grain is fed into a hopper 108 and then enters the thrashing mechanism 75, the thrashed grain which passes through the concave being collected upon the table 30.

While the thrashed straw is discharging over the open support it is acted upon by a rotatable agitator or beater 109, rigidly secured to a transverse shaft 110, journaled through suitable bearings carried by the framework 20, the shaft 110 being provided at one end with a pulley to drive it.

The shaft 116 may be considered a power shaft and carries a pulley 119, to be driven by a belt extending from an engine or other motor. This shaft is driven in the direction of its arrow.

The shaft 116 carries a pulley 119 engaged by a belt 121 which engages a pulley 79 on shaft 77, and also an idler 122. The lower run of the belt 121 is crossed and engages the pulley 58, which drives the conveyor and a fan within the casing.

The operation of the machine is as follows:

Straw with the grain thereon is fed into hopper 108 and enters the thrashing mechanism 75, wherein the same is thrashed. A portion of the thrashed grain may fall through the concaves and be collected on tray 30 a portion of which is indicated in Figure 1. The grain after leaving the thrashing cylinder is susceptible of treat-

ment in a thrasher of any approved construction.

I claim—

1. In a machine of the character specified, a thrashing mechanism comprising a plurality of concave sections, each section including sides arranged at an angle with relation to each other, a plurality of teeth carried by one side of each section, the other side without teeth, vertically adjustable supporting-means for said sections, means for slidably and pivotally connecting said sections with said supporting means, whereby said sections may be adjusted and turned upon their longitudinal axes, means for so turning said sections, means for vertically moving said supporting means; and a toothed rotatable drum disposed above the said concave sections. 75

2. In a machine of character specified, a thrashing mechanism including a plurality of concave sections, each section including angularly disposed sides, a plurality of teeth carried by one side of each section, the other side being without teeth, shafts extending through said sections and rigidly secured thereto, to turn the sections upon their longitudinal axis, supporting elements having elongated horizontally disposed slots, said shafts mounted in said slots, means for turning said shafts, pinions on the opposite ends of said shafts, arcuate racks carried by said supporting elements, and engaging said pinions, and a toothed rotatable drum disposed above said concave sections. 85

3. In a machine of the character herein specified, a thrashing mechanism, including a plurality of concave sections, each section comprising angularly disposed sides, a plurality of teeth projecting from one of said sides, and the other of said sides being toothless, shafts extending through said concave sections and rigidly secured thereto, to turn said sections on their longitudinal axis, pivotally mounted supporting plates having elongated slots to receive said shafts, gears carried by the shafts, arcuate racks secured to the outer faces of said pivotally mounted supporting plates, and engaging said gears, means for turning said shafts, means for swinging the supporting plates whereby they will maintain concentricity with the thrashing drum, and a rotatable toothed drum disposed above said sections. 105

ROBT. H. OWEN.
